(57) **CLAIM**

The ornamental design for a phone case, as shown and described.

DESCRIPTION

FIG. 1 is a front perspective view of a phone case in an open configuration showing a first embodiment of my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of the first embodiment of the phone case in an alternate open configuration;

FIG. 9 is a perspective view of the first embodiment of the phone case in a closed configuration;

FIG. 10 is a front perspective view of the first embodiment of the phone case in another alternate open configuration;

FIG. 11 is a front perspective view of a phone case in an open configuration showing a second embodiment of my new design;

FIG. 12 is a front view thereof;

FIG. 13 is a back view thereof;

FIG. 14 is a left-side view thereof;

FIG. 15 is a right-side view thereof;

FIG. 16 is a top view thereof;

FIG. 17 is a bottom view thereof;

FIG. 18 is a front perspective view of the second embodiment of the phone case in an alternate open configuration;

FIG. 19 is a perspective view of the second embodiment of the phone case in a closed configuration; and,

FIG. 20 is a front perspective view of the second embodiment of the phone case in another alternate open configuration.

The broken lines shown in the drawing figures depict portions of the phone case that form no part of the embodiment of the claimed design in which they are shown.

1 Claim, 20 Drawing Sheets
